UNITED STATES PATENT OFFICE.

WILLIAM G. PETERS, OF PEORIA, ILLINOIS, ASSIGNOR TO WESTINGHOUSE ELECTRIC & MANUFACTURING COMPANY, A CORPORATION OF PENNSYLVANIA.

WRINGER MOUNTING.

Application filed March 18, 1922. Serial No. 544,802.

This invention relates to improvements in wringers and wringer mountings. It pertains particularly to a wringer and wringer mounting used in connection with so called power washing-machines.

One of the objects of my invention is the construction of a wringer-mounting so arranged that the wringer may be moved to a variety of positions around the washing machine so that any desired wringing operations are possible.

Another object is that of so mounting a wringer that it may be swung in a horizontal plane to a variety of desirable positions around a power washing-machine with which it is used, and convey power to its rolls from the latter in any and every position it may occupy.

Another object of the invention is to provide a new manner of holding the wringer rolls in operative position and for releasing them instantly.

Still another object is that of providing a structure in a wringer-frame that will permit the upper wringer roll to be swung away from the lower one at an extremely wide angle to the end that repairs may be easily made and that replacement of worn or broken parts may be quickly and easily accomplished.

Further, an object lies in a new form of drain board attachment.

Figure 1 is an elevation of a wringer showing my invention in connection therewith mounted on a washing machine.

Figure 2 is a plan of a washing machine of the power type, showing my invention thereon, and a series of receptacles adjacent it, illustrating the manner of use of said invention.

Figure 3 is a sectional elevation of a wringer-supporting arm, showing a wringer mounted thereon and power connection for driving the wringer-rolls.

Figure 4 shows parts of my invention in perspective.

Figure 5 is a transverse sectional elevation of a wringer showing an adjustable drain board, and Figures 6, 7 and 8 are details thereof in perspective.

In the several figures a power washing-machine is designated at 1 having the cus-

tomary vertical driven shaft 2 with which my invention is related.

A hollow arm 3 is swiveled at one end of the machine receiving the end of the shaft 2 which is provided with a bevel gear 4.

Said arm is suitably mounted upon the machine 1 so that it may swing to any position but the method of mounting it will not require detailed description since any desired form of swivel may be employed. However, a band 3' is employed to frictionally engage a standard 3² and a depending part of the arm, being clamped to both by means of a lever 3³ whereby to secure said arm in a fixed position.

The arm is of arch-form, preferably, and has a shaft 5 mounted therein in suitable bearings 6. One end of the shaft carries a gear 7 to mesh with the gear 4, while at its other end it has a similar gear 8. The end of the arm opposite that mounted on the machine 1 has a hollow head 9 terminating in an upstanding flange 10.

The wringer includes upper and lower frame portions 11, 12 and the usual rolls 13, and 14. Extending from one end of the wringer is a casting 15 terminating in a hollow head 16, the shaft 17 of the lower so wringer-roll 14 extending through the casting into the said head. Said shaft has bearings suitably disposed in the structure for carrying it, and two spaced oppositely disposed bevel gears 18, 19 are loosely mounted so that the shaft may turn therein.

Keyed to said shaft between the gears is a clutch sleeve 20 adapted to slide along the shaft and to be placed in the neutral position shown. A lever 21 pivoted in the head 16 serving to operate the same.

Mounted in bearings 22 and 23 in the heads 9 and 16 respectively, is a shaft 24 having at its end within the head 16 a gear 24' to mesh with both gears 18, 19, while within the head 9 it has a gear 25 in mesh with the gear 8 of the shaft 5.

The head 16 includes a supporting flange 16' which rests upon the flange 10, the flanges having circumferential enlargements 16². A band 25' encircles the flanges and serves through a lever 26, Figure 1, to clamp the arm 3 and wringer in fixed positions relatively.

It is now clear that the arm 3 swiveled upon

the washing machine can swing to any position desired, and that the wringer, being swiveled at the other end of the arm, may swing in like manner.

As an example of the advantage of such an arrangement Figure 2 shows, rather diagrammatically, a washing machine upon which my invention is mounted and wherein 1 is the machine, 3 the arm and 11 the wringer.

B, C, D are tubs arranged in a line with the machine, and E a container such as a clothes basket, for example.

When mounted at one corner of the machine at X, for example, the wringer can be used, as shown in solid lines, to wring from the machine into the tub C as indicated by the dart a. Again when the arm is swung to a position at right angles as at b the clothes can be wrung from the machine as designated by dart c into any receptacle. Or, upon swinging the wringer to the position d, clothes may be wrung from tub B into the machine, or in a reverse direction as is obvious. When in positions e, f, the wringing may be from tub C into basket E or into tub D respectively while position g permits wringing from tub D to basket E. Other possible positions are shown in broken lines at h, i, j, k, l, m, n.

The foregoing is merely to indicate some of the possible combinations that may be used as showing the adaptability of the wringer and arm movement.

My invention besides the structure described also includes a very simple but effective manner of constructing a wringer so that its rolls may be quickly released under too great a load and that may be widely separated for making repairs and replacements.

The upper frame 11 previously referred to includes an abutment 11', Figure 4, to rest upon a portion 12' of the frame 12, while a portion 11² is hinged to a portion 12². A cam 11³ is formed with the abutment 11', and receives a roller 11⁴ of a bail or yoke 11⁵ pivoted on said abutment, there being an extension 11⁶ of said bail or yoke so disposed that the hand of the operator may strike the same to release the upper frame 11 on occasion. The disposition of the pivot of the bail is such, with respect to the cam, that when said bail is in engaging position the roll 13 will be brought down upon the roll 14 in proper working engagement as determined by the usual tension springs (not shown) of said wringer.

When the bail is thrown outward free of the cam 11³ the upper frame 11 can be raised and swung upward as shown in Figure 3, an extension 11⁷ of the portion 11² resting against one side of the latter sustaining said frame 12.

Thus arranged, either roll may be removed

with ease and any repairs may be quickly 65 and easily made.

In Figures 5, 6, 7 and 8 is shown a new arrangement in a wringer wherein the drain-board indicated at 27 may be adjusted to either of its two positions and held in place. 70

Mounted upon each side of the wringer is a drip board 28, not shown in Figure 3, having a downwardly and inwardly directed hook portion 29 at its outer extremity. The lower frame portion 12 of the wringer has 75 an upstanding longitudinal rib 30 which lies midway between the members 28. At 31 is a filler portion.

The drainboard pivotally carries on its under side a pair of spaced latches or dogs 32, one lying near each of its longitudinal edges. Said board is inserted beneath the roll 14, one edge being engaged with one of the hooks 29, Figure 5, the latch or dog 32 nearest that edge being then in position 80 to drop down and engage the said portion 31 at that side of the wringer. The board rests upon the rib 30 and is securely held by said dog. But by lifting the projecting edge of the board and moving the dog on its pivot to lift it from the portion 31 said board may be withdrawn, or by shifting it to the right as viewed in said Figure 5 it may be placed in the opposite position shown in 85 broken lines.

This is a very convenient arrangement and being simple in its appointments may be readily placed in position or changed in location at will while being held entirely rigid in either of its positions for use. 90

While my swinging arm and wringer is particularly designed for power washing machines from which driving power may be transferred to the wringer rolls, they may be mounted on any support even where power 100 is not available and where a hand operated wringer is used so that the wringer may be swung to a variety of positions above a series of wash tubs and operated by hand.

Although I have shown preferred arrangements of the parts of my wringer structure, various changes may be made without departing from the spirit and intent of the invention or from the scope of the claims. 110

I claim:—

1. The combination in a washing machine, with a power element therein, of an arm pivotally supported on said element, a wringer pivotally mounted on the arm remote from the point of support of the same, adapted 120 to swing in a horizontal plane, and gearing for transferring power through the arm from the element to the wringer-rolls, said gearing operating to drive said rolls in any position of the arm and wringer relatively. 125

2. The combination in a washing machine, with a power element therein, of an arm pivotally supported at said element, a wringer

pivotedly mounted on the arm remote from the point of support of the same, adapted to swing in a horizontal plane, and gearing for transferring power through the arm from the element to the wringer-rolls, said gearing operating to drive said rolls in any position of the arm and wringer relatively, and in any position of the arm relatively to the machine.

5 3. In combination with a support including a power shaft, an arm pivoted at one end

on the support adapted to swing around the shaft in a horizontal plane, a wringer pivoted at one end upon the other end of the arm adapted to swing in a horizontal plane, 15 power means within the arm operatively engaging the wringer-rolls and the said power shaft for driving the former, means to secure the arm and support relatively, and means to secure the wringer and arm relatively.

20 In testimony whereof I affix my signature.

WILLIAM G. PETERS.
